FIG. 1 is a front perspective view of a timer showing my new design;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a front elevational view thereof, the handle being shown in the unlocked position; and

FIG. 8 is a left side elevational view thereof.

The characteristic features of my new design reside in the upwardly inclined face of the timer and in the appearance of the substantially parallel upwardly inclined double-edge portions as seen on both sides of the face of the timer.

I claim:

The ornamental design for a timer, as shown.
